UNITED STATES PATENT OFFICE.

WILLIAM B. CUNNINGHAM AND PHILIP HILL, OF PHILADELPHIA, PA.

DESIGN FOR FRINGE.

Specification forming part of Design No. 5,425, dated December 19, 1871.

To all whom it may concern:

Be it known that we, WILLIAM B. CUNNINGHAM and PHILIP HILL, of the city and county of Philadelphia, State of Pennsylvania, have invented a new and ornamental Design for Fringe; and we do hereby declare the following to be a specification thereof.

The nature of our design is fully represented in the accompanying photographic illustration, to which reference is made.

Having thus described our invention, what we

claim as new, and desire to secure by Letters Patent, is—

The design for fringe, as shown.

To the above we have signed our names this 24th day of June, 1871.

W. B. CUNNINGHAM.
PHILIP HILL.
